UNITED STATES PATENT OFFICE.

OTHO A. BARBOUR, OF SAN DIEGO, CALIFORNIA, ASSIGNOR, BY DIRECT AND MESNE ASSIGNMENTS, OF ONE-THIRD TO WILLIAM T. BARBOUR, OF SAN DIEGO, CALIFORNIA, AND ONE-THIRD TO LEWIS J. ACKERS, OF POMONA, CALIFORNIA.

COAT COLLAR.

1,408,492.

Specification of Letters Patent.

Patented Mar. 7, 1922.

Application filed September 27, 1920. Serial No. 412,949.

To all whom it may concern:

Be it known that I, OTHO A. BARBOUR, a citizen of the United States, residing at San Diego, in the county of San Diego and State of California, have invented certain new and useful Improvements in Coat Collars, of which the following is specification, reference being had to the accompanying drawings.

10 This invention relates to coat collars.

An important object of the invention is to provide a coat collar which is unstretchable longitudinally.

It is a well known fact that a coat, the collar of which originally fitted, if suspended by the collar, loses its shape at the collar due to the fact that the fabric of the collar stretches longitudinally, giving an excess length in the collar often amounting to as much as two and one-half inches, and results in the collar setting away from the neck of the wearer and presenting an unsightly appearance. In order to correct the appearance of the collar the services 25 of a tailor are necessary, resulting in a loss of time and the cost of the tailor's services.

My invention, accordingly, consists in the combination with the collar of an element, extending longitudinally thereof and secured to the collar, which is substantially non-extensible, as for example, a band of unstretchable tape. This "unstretchable" medium is preferably secured to the collar by securing the same to the stiffening element 35 utilized to support the collar, as will hereinafter be set forth.

In the accompanying drawings, wherein for the purpose of illustration and wherein like reference characters designate like parts 40 throughout:

Figure 1 is a fragmentary side elevation partly in section showing a collar constructed in accordance with my invention applied to a coat, and

45 Figure 2 is a section on the line 2—2 of Figure 1.

Figure 3 is a detail perspective of a section of the collar with parts broken away to more clearly illustrate the application 50 of the reinforcing strip.

Referring now more particularly to the drawings, the collar C is composed of an outer portion 10 or collar proper, and an inner portion 11 or neck band. These por-

tions are formed by employing an outer 55 layer 12 of material and an inner layer 13, and the usual stiffening medium 14 disposed intermediate the layers and secured to the layer 13 of the material in the usual manner and folding the same longitudinally. 60 In attaching the collar to the coat the outer layer 12 of the material is secured to the lining L of the coat and the inner layer or that layer forming the inside of the collar after the folding thereof is secured to the 65 material M of the coat. Extending longitudinally of the upper edge of that portion of the stiffening medium disposed intermediate that portion of the layers forming the neck band 11, is a tape 15 of such weave 70 that the same affords great resistance against longitudinal extension thereof. This tape is secured to the stiffening medium and to the layer 13 by stitching 16 extending therethrough. The ends of the tape do not 75 terminate with the ends of the collar proper, but are extended there beyond for a distance of approximately an inch and a half, as indicated at 17, and when the collar is applied to the coat these loose ends 17 are 80 secured to the stiffening medium 18 of the breast of the coat by stitching 18^a, thereby preventing sagging of the upper portion of the lapels, at which point a great deal of stretching occurs due to the fact that heavy 85 articles are often placed in the pockets of the coat.

The tape 15, being non-extensible longitudinally, will effectually resist any stretching of the material of the collar which would otherwise be present, thereby materially assisting in maintaining a fresh appearance to the coat and likewise adding to the life thereof. It will be obvious that instead of employing a tape, as described, any other 95 suitable textile of relatively low ductility might be employed with the same result without in any manner departing from the spirit of my invention. I accordingly do not limit myself to the specific construction 100 hereinbefore set forth, except as so limited by the subjoined claims.

Having now described my invention, what I claim is:

1. The combination with a collar embodying inner and outer layers folded to form a neck band and an outer collar, of a strip of material of relatively low ductility as

regards the remaining material of the collar disposed intermediate said layers of material and secured to one thereof adjacent the line of fold of the material, the said ends of said strip of material extending beyond the ends of the collar.

2. The combination with a collar comprising inner and outer layers having interposed therebetween a stiffening medium, 10 said inner and outer layers and stiffening medium being folded approximately centrally longitudinally thereof to form a neck band and an outer collar, of a strip of tex-

tile material of relatively low ductility as regards the remaining material of the collar 15 secured to the face of the stiffening material at the upper edge of that portion thereof forming the neck band and extending longitudinally of said upper edge, the ends of said strip of material extending beyond the ends of the collar and being adapted for attachment to the stiffening material of the breast of the coat.

In testimony whereof I hereunto affix my signature.

OTHO A. BARBOUR.
